(57) **CLAIM**

The ornamental design for a boot cleaning and sanitizing device, as shown and described.

DESCRIPTION

FIG. 1 is a perspective view of the boot cleaning and sanitizing device.

FIG. 2 is a top plan view of the boot cleaning and sanitizing device.

FIG. 3 is a side elevation view of the boot cleaning and sanitizing device.

FIG. 4 is an end elevation view of the boot cleaning and sanitizing device.

FIG. 5 is an opposite end elevation view of the boot cleaning and sanitizing device; and,

FIG. 6 is a bottom plan view of the boot cleaning and sanitizing device.

The broken lines shown on the bracket portion in FIGS. 1 and 3 are for illustrative purposes only and form no part of the claimed design.
